UNITED STATES PATENT OFFICE.

ANDREW HUGH REID, OF TORONTO, ONTARIO, CANADA.

INCINERATOR.

1,126,866.

Specification of Letters Patent.

Patented Feb. 2, 1915.

Application filed February 21, 1914. Serial No. 820,283.

To all whom it may concern:

Be it known that I, ANDREW H. REID, of the city of Toronto, in the Province of Ontario, Canada, have invented certain new 5 and useful Improvements in Incinerators, of which the following is a specification.

This invention relates to incinerators or crematories in which garbage and the like is burned on grates in a chamber through which 10 the products of combustion travel to a chimney at one end. In such incinerators much difficulty is experienced in arranging the draft to secure equality of combustion at all points along the length of the furnace, it 15 generally being found that near the chimney the combustion is much more rapid than at the far end owing to the progressive heating of the air admitted to the far end as it travels toward the chimney. I overcome the 20 difficulty by admitting the air to the far end of the chamber through one or more draft tubes which lead through the chamber in such a manner that the air passing through 25 the tubes is highly heated before being discharged in proximity to the combustible material on the grates or arches of the incinerator, and by so constructing the end of the chamber adjacent the stack that the 30 draft is baffled to prevent the direct passage of the products of combustion to the stack, substantially as hereinafter more specifically described and definitely claimed.

Figure 1 is a longitudinal section of my improved incinerator. Fig. 2 is a cross section of the same looking toward the outlet end. Fig. 3 is a horizontal section on the line *a*—*a*, Fig. 1. Fig. 4 is a horizontal section on the line *b*—*b*, Fig. 1. Fig. 5 is a plan view.

40 In the drawings like numerals of reference indicate corresponding parts in the different figures.

1 is an incinerator comprising a chamber communicating at one end with a chimney 2 in a manner hereinafter described. The chamber is provided with the fire grates 3, above which are located the arches 4. Garbage to be cremated is dumped on these arches through the openings 5 in the top of the chamber, and after drying out there, falls or is raked through to be burned on the grates below. Sometimes, however, these arches are omitted, and my improvements are equally well adapted to an incinerator in which they are omitted. Various doors 6

are employed for use in raking off the arches and fire grates or cleaning out ashes. From the end of the chamber distant from the chimney, I lead one or more draft tubes 7. These tubes slide through holes in the roof 60 of the chamber so that they may be raised or lowered to bring their lower ends to position above or below the arches as may be desired. These draft tubes are preferably two in number and are located close to the 65 central vertical longitudinal plane of the chamber, and their lower ends are preferably turned so as to partly point toward the distant end of the chamber. These tubes are preferably of metal and hence are good 70 conductors of heat. The air passing through them is strongly heated before it emerges from their lower ends, hence a blast of hot air is provided for the combustion of the garbage at the end of the chamber 75 remote from the chimney, where under ordinary conditions the garbage is greener and therefore burns less readily than at the chimney end of the chamber. By introducing the air in this way I markedly increase the 80 quality of the incineration and conduct the process with far less inequality in temperature at different parts of the chamber than with the old arrangement in which air is admitted through the various doors as might 85 be desired. Of course, the use of my draft tubes does not prevent the use of other draft openings, as air may be still admitted through any of the doors if the circumstances seem to warrant it.

90 The use of draft tubes, I find produces a very strong and concentrated flow of air and products of combustion toward the chimney so that a very great tendency exists to carry 95 lighter portions of the garbage in an unconsumed or partly consumed condition right into the chimney. I find it essential therefore to baffle the draft so as to diffuse the air currents more equally through the chamber and to prevent a direct passage 100 from the draft tubes to the outlet. I therefore provide the baffle wall 8 across the end of the chamber in front of the outlet 9 leading to the stack. This wall is sufficiently spaced from the end of the chamber to form 105 plumes behind it communicating with the outlet 9 forming the opening to the chimney. Openings 10 are formed through this baffle wall at each side of the chamber. Currents 110 of air and the products of combustion com-

ing in a direct line from the draft tubes strike the baffle wall, are deflected outwardly to the openings 10, thence behind the baffle wall to the outlet 9. As gases tend to accumulate in the top of the chamber which might ultimately form an explosive mixture, it is necessary to draw these off. I therefore provide the second outlet 11 near the top of the chamber communicating with the chimney. This outlet may be of considerably smaller dimensions than the outlet 9, and as the flow of the gases and products of combustion in the top of the chamber is less rapid than in the lower part of the chamber, the openings 12 which are formed through the baffle wall at the sides of the chamber may be considerably larger than the openings 10. The baffle wall is thus comparatively narrow in front of the outlet 11.

A transverse shelf 13 extends from the baffle wall 8 to the end of the chamber above the openings 10 and just at the lower edge of the openings 12 so as to completely separate the products of combustion passing to the outlet 9 from those passing to the outlet 11. The equality of operation at different parts of the chamber is much facilitated by the introduction of the longitudinal wall 14 which extends from end to end of the chamber and is preferably projected into the outlet 9 so as to practically divide the outlet 9 into two parts. This wall extends only part way up the chamber, and serves to support the inner ends of the arches 4. The burning of the garbage after drying is thus in effect carried out in two long and comparatively narrow chambers in which the combustion can be much more effectively carried out than in a wider chamber. This division is not essential in the upper part of the chamber where practically only drying is carried out.

I find that an incinerator constructed as shown and described is very effective in operation, no special fuel whatever being required except perhaps a little in starting operations. Once the incinerator is in operation, its action is continuous without the use of special fuel, and it may be run at full draft or banked for considerable lengths of time if desired and when awaiting fresh supplies of garbage for consumption.

What I claim as my invention is:—

55. 1. An incinerator comprising a chamber provided with fire grates; arches above the grates; a chimney communicating with the chamber at one end both above and below the arches; a draft tube leading through the chamber from the outer air to a point adjacent the end of the chamber distant from the chimney whereby air is heated and brought into proximity to the combustible material distant from the chimney; and a baffle wall at the end of the chamber adja-

cent the chimney provided with openings above and below the arches and adapted to prevent the passage of the products of combustion in direct lines to the chimney.

2. In an incinerator, a chamber provided with fire grates; arches above the grates; a chimney communicating with the interior of the chamber by openings at different levels substantially midway between the side walls; a baffle wall in front of said chimney having openings therein adjacent the sides of the chamber both at top and bottom, leading respectively from the spaces in the chamber above and below the arches; and a transverse shelf extending from the baffle wall to the end of the chamber between the upper and lower chimney openings.

3. In an incinerator, a chamber provided with fire grates; arches above the grates; a chimney communicating with the interior of the chamber by openings at different levels substantially midway between the side walls; a baffle wall in front of said chimney having openings therein adjacent the sides of the chamber both at top and bottom, leading respectively from the spaces in the chamber above and below the arches; a transverse shelf extending from the baffle wall to the end of the chamber between the upper and lower chimney openings; and a longitudinal wall extending partway up toward the top of the chamber and from end to end, said wall extending to the lower chimney opening.

4. In an incinerator, a chamber provided with fire grates; arches above the grates; a chimney communicating with the interior of the chamber by openings at different levels substantially midway between the side walls; a baffle wall in front of said chimney having openings therein adjacent the sides of the chamber both at top and bottom, leading respectively from the spaces in the chamber above and below the arches; a longitudinal wall extending partway up toward the top of the chamber and from end to end, said wall extending to the lower chimney opening; a transverse shelf extending from the baffle wall to the end of the chamber between the upper and lower chimney openings and a draft tube leading from the chamber to the outer air to a point adjacent the combustible material distant from the chimney.

5. In an incinerator, a chamber provided with fire grates; a chimney at one end communicating by a suitable opening with the interior of the chamber substantially midway between the side walls; a baffle wall in front of said chimney opening having openings therein adjacent the side of the chamber both near the grates and toward the top of the chamber; and a draft tube leading through the chamber from the outer air at the top of the incinerator to a point adja-

cent the central longitudinal vertical plane of the chamber at the end distant from the baffle wall.

6. In an incinerator, a chamber provided with fire grates; arches above the grates; a chimney communicating with the interior of the chamber by openings at different levels substantially midway between the side walls; a baffle wall in front of said chimney having openings therein adjacent the sides of the chamber both at top and bottom leading respectively from the spaces in the chamber above and below the arches; a transverse shelf extending from the baffle wall to the end of the chamber between the upper and lower chimney openings; a longitudinal wall extending partway up toward the top of the chamber and from end to end, said wall extending to the lower chimney opening; and two draft tubes leading through the chamber from the outer air each adapted to discharge at a point adjacent the central longitudinal vertical plane of the chamber at the end distant from the baffle wall.

7. In an incinerator, a chamber provided with fire grates; arches above the grates; a chimney communicating with the interior of the chamber by openings at different levels substantially midway between the side walls; a baffle wall in front of said chimney having openings therein adjacent the sides of the chamber both at top and bottom; leading respectively from the spaces in the chamber above and below the arches; a longitudinal wall extending partway up toward the top of the chamber and from end to end, said wall extending to the lower chimney opening; and two draft tubes leading through the chamber from the outer air each adapted to discharge at a point adjacent the end of the chamber distant from the baffle wall. 30 35 40

Dated at Toronto, Ontario, Canada, this 14th day of February, 1914.

ANDREW HUGH REID.
